(57) **CLAIM**

The ornamental design for a retractable personnel barrier, as shown and described.

DESCRIPTION

FIG. 1 is a top, front, left side perspective view of a partially extended retractable personnel barrier showing my new design;

FIG. 2 is a front elevational view of the design in the retracted mode;

FIG. 3 is a top plan view thereof;

FIG. 4 is a bottom plan view thereof;

FIG. 5 is a left side elevational view thereof;

FIG. 6 is a right side elevational view; and,

FIG. 7 is a rear elevational view thereof.

The black and white stripes show contrasting colors of the design.
